[57] **CLAIM**

The ornamental design for a wall-mounted fold-down bicycle storage rack, as shown and described.

DESCRIPTION

FIG. 1 is a top, front, and right side perspective view of a wall-mounted fold-down bicycle storage rack showing my new design;

FIG. 2 is an enlarged front elevational view thereof;

FIG. 3 is an enlarged right side elevational view thereof, the left side being a mirror image of that shown;

FIG. 4 is an enlarged rear elevational view thereof;

FIG. 5 is an enlarged top plan view thereof; and,

FIG. 6 is an enlarged bottom plan view thereof.

FIG. 2

FIG. 4

FIG. 5

FIG. 6
